ATTORNEYS

UNITED STATES PATENT OFFICE.

IDA K. MARTIN, OF MINNEAPOLIS, MINNESOTA, ASSIGNOR TO NATIONAL WOMAN'S RELIEF CORPS, OF DECATUR, ILLINOIS, A CORPORATION OF ILLINOIS.

DESIGN FOR A FLAG STAND.

Application filed October 1, 1923. Serial No. 7,375. Term of patent 3½ years.

To all whom it may concern:

Be it known that I, Ida K. Martin, a citizen of the United States, residing at Minneapolis, in the county of Hennepin and State of Minnesota, have invented a new, original, and ornamental Design for a Flag Stand, of which the following is a specification, reference being had to the accompanying drawing, forming part thereof.

I claim—

The ornamental design for a flag stand as shown.

IDA K. MARTIN.
